UNITED STATES PATENT OFFICE.

JOHN W. CURRAN, OF NEWPORT, KENTUCKY.

SAFETY-APPLIANCE RIVET-BOLT.

No. 845,698.

Specification of Letters Patent.

Patented Feb. 26, 1907.

Application filed December 1, 1906. Serial No. 345,927.

To all whom it may concern:

Be it known that I, JOHN W. CURRAN, a citizen of the United States, and a resident of Newport, in the county of Campbell and State 5 of Kentucky, have invented certain new and useful Improvements in Safety-Appliance Rivet-Bolts, of which the following is a specification.

My invention is an improvement in safety-appliance rivet-bolts especially intended for use on railway-cars; and the invention consists in certain novel constructions and combinations of parts, as will be hereinafter described and claimed.

15 In the drawing, Figure 1 illustrates my invention in connection with a grab-iron. Fig. 2 illustrates the invention in connection with a brake-staff stand. Fig. 3 shows the invention in connection with an air-pipe clamp. Fig. 4 shows the improved bolts in connection with a sill-step. Fig. 5 illustrates the invention in connection with a stake-pocket. Fig. 6 is a side view of an unthreaded bolt in connection with a portion of a car, 20 the latter being shown in section. Fig. 7 is a similar view, the bolt being threaded. Fig. 8 is a side view of the bolt previous to being riveted. Fig. 9 is a side view, and Fig. 10 is an end view, of the bolt, showing a key applied. 25 The object of the invention is to simplify the present methods of applying grab-irons, sill-steps, uncoupling-lever brackets, stake-pockets, air-pipe clamps, retaining-valves, brake-staff stands, &c., to steel freight-cars. 30 The present methods when one of the steps, clamps, or the like becomes broken necessitates the moving of the freight inside the car in order to get at the rivets for cutting out the same.

35 My invention seeks to provide for replacing any of the devices held by the safety-bolts without necessitating going inside the car or any movement of the freight, so that in a few minutes repairs may be made without taking 40 the car out of the train and without getting under the car. Repairs of this character are now made under conditions that make them very expensive for the railroads, as the cars must be taken to the repair-track, frequently 45 causing a delay of twenty-four to forty-eight hours, and the importance of ready repairs will be appreciated when it is understood that the Government imposes a heavy fine on any railroads whose inspectors are detected 50 running cars by terminals with defective safety-appliances.

The present improvement facilitates the making of repairs, so that many repairs may be made which would not otherwise be made under existing circumstances, so that its adoption will help the railroads as well as advance the aims of the Government.

By my invention I provide a safety-bolt permanently in connection with the cars, so that when grab-irons, sill-steps, &c., become 60 broken they can be easily removed and replaced.

As shown, the bolt A may be slotted, as shown at A', to receive a key B, or the slot may be omitted, as shown at A², Fig. 1, and the bolt be threaded to receive a nut C, as illustrated in the said Fig. 1, for securing the grab-iron in place. Throughout the construction the bolts are shouldered at a to abut the outer face of the car side D and are 70 provided with tenons a', which project through openings d in the car side and are riveted at their inner ends at a², forming heads, whereby the bolts are permanently secured to the car side at their inner ends and 75 project outwardly therefrom to receive any one of the irons, such as shown at 1, 2, 3, 4, and 5 in the accompanying drawing, which irons may be of the ordinary construction generally employed for the purpose for which 80 they are designed. These irons have openings fitting over the bolts, and when so fitted, as shown in the figures, nuts C may be applied, as shown in Fig. 1, or the keys may be driven home, as shown in Figs. 2, 9, and 10, 85 to secure the irons in place.

With a bolt arranged as shown the irons may be applied from the outer side of the car, and thus save the expense and delay of moving the freight to get at an ordinary bolt or 90 rivet within the car.

The construction is simple, can be economically applied, and will result in a great saving of time and money.

It is found in practice that bolts and rivets 95 securing grab or other irons rarely, if ever, become broken, and by making the bolts permanently in connection with the cars I provide for the ready substitution of new irons whenever desired.

I claim—

1. The combination with a car having openings, of a rivet-bolt shouldered near its inner end to abut the car side and having beyond said shoulder a tenon projecting through the opening in the car side and riveted at its inner end forming a head bearing against the

inner face of the car side, an iron fitting on said bolt on the outer side of the car, and means in connection with the bolt beyond said iron for securing the latter in place, substantially as set forth.

2. A car having a bolt provided near its inner end with a shoulder abutting the outer face of the car and having a tenon beyond said shoulder and projecting through the car

and riveted on the inner side of the car, the outer end of the bolt being threaded, an iron fitting on the bolt and against the face of the car, and a nut on the bolt for securing said iron, substantially as set forth.

JOHN W. CURRAN.
